UNITED STATES PATENT OFFICE.

GEORGE B. KOHLER, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

PASSENGER-CAR.

1,152,108.

Specification of Letters Patent. Patented Aug. 31, 1915.

Application filed January 11, 1912. Serial No. 670,566.

To all whom it may concern:

Be it known that I, GEORGE B. KOHLER, a citizen of the United States, residing at 2221 South Sixty-third street, in the city 5 of Philadelphia, county of Philadelphia, and State of Pennsylvania, have invented certain new and useful Improvements in Passenger-Cars, of which the following is a full and clear and exact description.

10 My invention has for its object the improvement in what are called "semi-convertible" cars, in which the sashes or closures may be raised or lowered to open or close the windows, so as to expeditiously 15 convert the car into a semi-open car and in like manner convert the same into a closed car, for seasonable use.

The object of my invention is to improve the details of construction of the window 20 sashes, the means for guiding them into and out of the storage spaces under the roof of the car, and for suspending them therein, and during their intermediate movements; to the end that more certain and expeditious 25 operation and suspension of the sashes may be had, the stability of the construction improved, and the cost of their production economized in.

My invention, therefore, resides in the 30 various constructions and combinations of parts hereinafter described and set forth in the claims appended hereto.

In the accompanying drawing forming part of this specification: Figure 1 is a sectional view of a car showing the sashes in the raised position to open the sides of the car. Fig. 2 is a similar view showing the sashes lowered to close the windows. Fig. 3 is a front view of a portion of the upper 40 and lower sashes, they being cut away to save room in illustration. Fig. 4 is an end view of Fig. 3. Fig. 5 is a sectional view on the line 5—5, Fig. 3. Fig. 6 is a perspective view of a portion of the upper and lower 45 sashes detached from each other. Figs. 7 and 8 are respectively front and side views illustrating one of the guide-clamps for the upper sash engaging the flexible guide-rail. Fig. 9 is a perspective view of the guide- 50 clamp, its parts being shown detached; and Fig. 10 is a perspective and sectional view of a modified form of sash connection.

Similar numerals of reference indicate like parts throughout the several views.

55 The car is of the conventional or other

form, and just sufficient of it is shown and described to illustrate the application of my improvements thereto.

At D is shown the belt rail, which constitutes the lower or horizontal portion of the 60 window opening.

At D² are the side posts or stanchions, which support the upper portion of the car comprising the roof D', the upper ribs D³, the lower ribs D⁴ and the head-lining D⁵. 65 The spaces between the roof D' and head-lining D⁵ form pockets or storage spaces d' for the retention of the window sashes when in the raised position. These spaces may be divided longitudinally of the car by a continuation or horn D⁶ of the posts D², both of which are "halved" into each other or have abutting shoulders as at D⁷, Fig. 1. The lower end of the head-lining D⁵ is secured to a projection D⁸ on the posts, and between the roof and the posts D² extends the letter board D⁹. The belt rail D and letter board D⁹ constitute the upper and lower vertical limits of the window openings, and the spaces between the posts D² determine the longitudinal dimensions of the window openings. On each side of the posts is affixed a parting strip D¹⁰, the outer edge of which with the flange D¹² of the post forms a groove to be hereinafter described.

In the foregoing manner, a car can be provided with efficient window openings and roof storage-spaces to permit of the application of my improvements, which I shall now describe.

At A and B are respectively the upper and lower sashes. These sashes may be efficiently connected by any particular form of hinge, but I prefer the form shown herein, comprising the hinge-plates F having securing sections f, which are secured to and overlap the face of the lower corner of the upper sash A, as shown in Figs. 3 and 6, and which have downwardly extending lugs or extensions f', from the inner faces of which pintles f² extend inwardly. The lower sash B is recessed at i to receive the extensions f' of the hinge plates F, and has a hole i' into which the pintles extend. The radius of the curve of the joint between the two sashes is at the center line of the pintles. This hinge construction provides a flexible or pivotal union of the two sashes, effectively hinging them together, and uniting 85 95 100 105

them against lateral movement independently of each other.

As shown, the two sashes are arranged in tandem, one on top of the other and in vertical alinement, when lowered. In other words they abut end to end, and lie in the same general plane when lowered and follow each other in their movements without braking joints. In order to allow the meeting edges or rails a , b , of the two sashes to move upon each other without undue friction and at the same time provide a weather tight joint, I may and prefer to use the construction shown in Figs. 5 and 6, or the modified form of construction shown in Fig. 10. In the former views, each sash A and B has a metal frame a' and b' , the cross pieces a^2 and a^3 respectively of said frames being concave and convex so as to constitute an articulated joint, and into these frames the lower cross piece m of the upper sash A and the upper cross piece n of the lower sash B are laid. In Fig. 10, the cross piece m' of the upper sash A' is set within the frame a' corresponding with the frame a' of Figs. 5 and 6, and the lower sash B' is provided with a frame b^2 embracing the upper cross piece n' of the sash, from which frame b^2 extends a rounded and preferably tubular rib b^3 which enters into the concave portion a^3 of the frame a' , the tubular rib b^3 being connected to the frame b^2 by the intermediate section b^4 . It will be understood that glass is secured to the sashes A and B and A' and B' as shown, in any desired manner.

It is manifest that the positions of the pintles f^2 , their attached parts, and the hole i' and recesses i may be reversed without affecting the mode of operation of the parts. And the same is true of the surfaces a^2 , a^3 , and the rib b^3 .

The space between the parting-strip D^{10} and the outer face of the post D^2 constitutes a groove d , which for a substantial portion of its distance from the belt-rail D is of a width sufficient to receive the lower sash and hold it firmly in position when the same is lowered and rests on the belt-rail, as shown in Fig. 2, but which for a substantial distance above the belt-rail increases in width and merges into the space d' between the roof D' and head-lining D^5 , so as to enable the sash to be raised and lowered with facility and to be retained in a weather tight condition when in such lowered position. The sashes being flexibly connected by a suitable hinge construction they can be raised and lowered together and yet be free to assume any desired angle with respect to each other and the groove d .

Means for suspending the sash, when raised and contained within the roof spaces, for effectively supporting the sash at its intermediate stages of movement between the lowered and completely raised position, and

for holding the upper edge of the upper sash against the lower edge of the letter-board to provide a weather tight joint and prevent rattling when the sashes are in their lowered position, is provided by the devices 70 now to be described.

At c is a preferably flat guide-rail. At its lower end, it is preferably secured to the letter board near the latter's lower edge, as shown in Figs. 1 and 2, and its upper end 75 to an appropriate part of the rib D^3 or an extension therefrom. This guide-rail is preferably made of metal, so that a portion of the guide-clamp hereinafter to be described, can be moved between the outer 80 surface of the rail, the rib D^3 and the letter-board D^0 . The upper end of the guide-rail c extends far enough into the roof space to allow the entire sash to be inclosed within the roof. At D^{11} is a rib which extends upwardly from the head-lining D^5 and which acts as a support for the upper sash A when it is in its raised position, as shown in Fig. 1. There are two of these guide-rails, each located within the plane of the sides of the 90 sash; and to provide an efficient means for permitting the sash to engage the guide-rail, I employ the guide-clamps shown in detail in Figs. 7, 8 and 9. Each guide-clamp, which I generally indicate by C , consists of the plate C' secured to the sash A, and projecting from its flange C^2 (which rests on the top rail of sash A) are lugs c' , to which is pivoted by the pin e the yielding pressure-finger E. The laterally extending 100 lip e' of this presser-finger rests against the outer face of the guide-rail c (see Fig. 8), the guide-rail lying between the face e' and the face of the upper sash. The presser-finger E has a depending stem e^2 , and lying 105 between the stem and a plate e^3 , which connects the lugs c' , is a spring g which tends to force the lip e' of the presser-finger against the rail c , so that as the sashes are raised and lowered the guide-clamp C will 110 travel on the guide-rail c , the clamp yielding, so as to prevent its binding on the guide-rail, but engaging it with sufficient friction to hold it suspended at any desired point. 115

When in the raised position, as shown in Fig. 1, the rib D^{11} supports the upper sash and enables both sashes to be supported within the roof space without requiring as much of a projection thereof into the roof space, in 120 order to clear the upper portion of the window opening, as would be required if the sashes were permitted to lie with their planes more nearly parallel.

When in the lowered position, the engagement of the presser-finger E with the guide-rail c at the point where the said rail is secured to the letter-board D^0 causes the upper edge of the sash A to be forced against the letter-board D^0 , (as shown in Fig. 2) 130

and this, and the engagement of the sash with the groove d at the belt-rail D and for some distance above it, causes the sash to be held firmly in position to close the window 5 opening.

The sash B is provided with hand pulls B², by means of which both sashes may be raised and lowered into the storage position shown in Fig. 1, or pulled down into the 10 closed position shown in Fig. 2, or adjusted to any intermediate position.

While I have shown and described herein a certain specific form of guide clamp and specific forms of sash-joints, I make no claim 15 to the same as such herein, and reserve the same for further applications for patent.

It is apparent that the above described embodiment of my invention may be modified in many details without departing 20 from its spirit. Therefore, I do not limit myself to the exact forms shown herein, but consider that my invention is as broad as the scope of the claims appended hereto.

What I claim is:

25 1. A car having side posts provided with opposing guide ways and a roof space into which said guide ways merge, a guide rail in said roof space combined with said guide ways, a two-part sash flexibly secured together end to end, and a guide clamp secured to the upper sash and movably engaging the guide rail.

30 2. A car having side posts provided with opposing guide ways and a roof space into 35 which said guide ways merge, a guide rail in said roof space combined with said guide ways, a two-part sash flexibly secured together end to end, a guide-clamp secured to the upper sash and movably engaging the 40 guide rail, and a support extending upwardly from the head-lining into the roof space and adapted to engage one of the sash elements to support the sash in the roof space above the head-lining.

45 3. A car having posts, opposing grooves in said posts, a roof space, said grooves increasing in width to and merging into the roof space, a guide rail the upper end of which is secured within said roof space, and 50 a sash comprising a plurality of sections flexibly connected end to end, adapted to move in said grooves, and a guide-clamp secured to said sash and adapted to movably engage the guide rail.

55 4. A car having posts, opposing grooves in said posts, a roof space, said grooves increasing in width to and merging into the roof space, a guide rail, the upper end of which is secured within said roof space, a 60 sash comprising a plurality of sections flexibly connected end to end, adapted to move in said grooves, a guide clamp secured to said sash and adapted to movably engage the guide rail, and a support extending upwardly from the head-lining into the roof

space and adapted to engage one of the sash elements to support the sash in the roof space above the head-lining.

5. A sash comprising two parts abutted end to end and articulated together, plates 70 F secured at the corners of one sash, projections f' extending from said plates, pintles f² extending inwardly from said projections and recesses in the opposing section adapted to movably receive said projections 75 and pintles, combined with grooved posts and a roof space, and means for guiding the sash therein.

6. A car window sash comprising two sections having upper and lower cross bars, 80 channel-shaped frames receiving said cross bars, the cross piece of one frame having a convex extension movably engaging a concave depression in the cross piece of the other channel frame, and additional means 85 for flexibly uniting the abutting ends of the sash sections together combined with grooved posts and a roof space, and means for guiding the sash therein.

7. The combination of a frame of a car 90 having guide ways at each side, of a window opening, a roof having a space to receive the sash, curved guide rails in the roof, an upper and a lower sash pivotally connected and adapted to the guide ways, flexible 95 guides on the upper end of the upper sash, each consisting of a plate, a pivoted presser-finger arranged to bear against the guide rail, and a spring located between an arm on the presser-finger and the plate. 100

8. The combination with the frame of a car having guide-ways at each side of a window opening, a roof having a space to receive a sash, curved guide rails in the roof, a sash adapted to the guide way, guide-clamps on the upper end of the sash each comprising a plate, an upwardly extending projection from the plate, a presser-finger pivoted to said projection and having on one 105 end a lateral extension, a stem opposite said extension, and a spring interposed between the stem and the said projection adapted normally to move the said lateral extension toward its pivot.

9. The combination with the frame of a 110 car having guide ways at each side of a window opening, a roof having a space to receive a sash, curved guide rails in the roof, a sash adapted to the guide-ways, guide clamps on the upper end of the upper sash, each comprising a presser-finger E having a laterally projecting lip e' and an oppositely disposed stem e², the plate C' having a flange C², upwardly extending lugs c' connected by a plate e³, the presser-finger being 115 pivoted within the lugs c' so as to cause the lip e' to lie laterally thereof, and a spring interposed between the plate e³ and the extension e². 120

10. The combination with the frame of a 125

car having guideways at each side of a car window and a roof having a space to receive the same, of sashes connected in tandem, a guide rail arranged within said space, a guide clamp secured to the top edge of the upper sash and having means for yieldingly engaging said guide rail as the sashes are moved into open or closed position.

- 10 11. The combination with the frame of a car having guideways at each side of a car window and a roof having a space to receive the same, of sashes connected in tandem, a guide rail arranged within said space, a guide clamp secured to the top edge

of the upper sash and having means for yieldingly engaging said guide rail as the sashes are moved into open or closed position, and means within said space extending upwardly to form a support for the 20 upper sash when the latter is in its raised position.

In testimony whereof, I have signed my name to this specification, in the presence of two subscribing witnesses.

GEORGE B. KOHLER.
